UNITED STATES PATENT OFFICE.

FERDINAND A. WESSEL, OF BROOKLYN, NEW YORK, ASSIGNOR OF ONE-HALF TO AUGUST GIESE, OF SAME PLACE.

MECHANISM FOR CARRYING WIRES THROUGH CONDUITS.

SPECIFICATION forming part of Letters Patent No. 450,206, dated April 14, 1891.

Application filed September 24, 1890. Serial No. 365,949. (No model.)

To all whom it may concern:

Be it known that I, FERDINAND A. WESSEL, a resident of Brooklyn, Kings county, State of New York, have invented Improved Mechanism for Threading Wires and the Like Through Pipes, of which the following is a specification, reference being had to the accompanying drawings, forming part thereof, wherein—

- 10 Figure 1 is a top view, partly in section, of two conduits, one of which is shown in section, with my improved wire-carrying mechanism in position for action. Fig. 1^a is a top view of my improved mechanism, showing it contained within a conduit, which is represented in section, the two carriages of my mechanism being apart. Fig. 2 is a similar view to Fig. 1^a, but representing the two carriages in contact. Fig. 3 is a side view of my improved 15 mechanism with the carriages in contact, the mechanism being represented in a subway, which appears in section. Figs. 4 and 5 are enlarged horizontal sections on the line $k'k'$, Fig. 6, of the outermost or loose carriage, 20 showing the clamps respectively drawn in and pushed out. Fig. 6 is a detail vertical section on the lines c^2c^2 , Figs. 2 and 4, of the last-referred-to carriage. Fig. 7 is a detail vertical section on the plane of the line $c'c'$, 25 Fig. 1^a, looking outwardly—that is, in the direction of the arrow placed near said section-line $c'c'$, but showing the pins in the other end of the slots as they appear when the clamp is forced out. Fig. 8 is a detail cross-section through the wire-carrying mechanism and through the conduit embracing the same, the line k^2k^2 , Fig. 6, indicating the plane of section. Fig. 9 is an enlarged top view of the innermost end of the wire-carrying mechanism; and Fig. 10 is a detail vertical section of said end on the line c^3c^3 , Fig. 9. Fig. 11 is a top view of a modification of my improved mechanism, showing it within a conduit, which is represented in section; and Fig. 12 30 is a side view of said modification, showing it likewise within a conduit represented in section.
- The object of this invention is to provide means for drawing a wire, a cable, a rope, or 35 analogous thread through a long tube or conduit from end to end when such tube or con-
- duit has no facility for placing such thread into it through any longitudinal opening—in other words, a long tube open only at its ends is by my mechanism to be threaded with 40 a wire or cable or the like, so that for telegraphic, telephonic, and other electrical conductors ready means for placing them within conduits already in position shall be provided.
- To this end my invention mainly consists 45 of two self-clamping carriages and a suitable mechanism to move them from and to one another, one of said carriages being shown secured to a carrier or stem, while the other is shown adapted to slide on said shank or 50 stem, the combination operating in such a manner that while the outer carriage clamps itself tight within the conduit it is utilized as a bearing for drawing the stem and the remaining carriage inward, after which the inner carriage clamps itself tight in the conduit and allows the outer carriage to be drawn 55 up toward it, and thus a wire or set of wires attached to the central stem or carrier can gradually, by a step-by-step motion, be moved 60 into and through the entire length of the tube.
- In order to give a clear description of this invention with reference to the drawings, (omitting for the present Figs. 11 and 12,) I 65 will now proceed to describe said drawings.
- In the same the letter A represents a suitable tube or conduit through which the wires B B (see Fig. 1) are to be drawn, or, in other words, the tube A is to be threaded with the 70 wires B. These wires are secured by tying or otherwise to a stem or carrier C, which is as long as necessary for the purpose of this mechanism and straight for a straight tube, but may be correspondingly curved for a curved 75 tube. Supposing the stem C to be inserted into the tube A so that one end enters the tube while the other slightly projects therefrom, as in Fig. 1, we will call the one end which enters the tube the "inner" and the other end, which 80 projects therefrom, the "outer" end of the stem or shank. To the inner end is secured by a bolt *a* what I call the "inner carriage" D, and at a distance outward from this inner carriage D is fitted so as to be able to freely 85 slide the outer or sliding carriage E. The two carriages D and E are connected with 90
- 95
- 100

each other by strong springs F F, which have the tendency, normally, to draw the two carriages D E close together, as in Figs. 2 and 3, but which permit said carriages to be moved 5 asunder, as in Fig. 1^a.

In the drawings the stem or shank C is represented as being composed of two long parallel bars b b, which are rigidly connected together by a cross-pin d at or near their 10 outer ends, but which otherwise leave a free longitudinal passage between them for the play of the carriages and their parts, as will hereinafter more fully appear.

I will now proceed to describe the construction of the outer or sliding carriage E. The 15 said carriage consists, mainly, of a rigid frame which embraces the stem or shank C, and which is composed of two plates e e, that may have projecting ribs e² e², as shown in Fig. 8. 20 Each of said plates has the length of the carriage itself, the said plates being united into a rigid structure by vertical connecting-pieces g, there being also horizontal connecting-pieces f between the ribs e² for furnishing an 25 attachment to the end of the spring F. The frame e g of this carriage E thus constructed is free to slide on the stem or shank C, and in turn the stem or shank C is free to slide within said carriage E. Near the inner end of the 30 carriage E is placed a sliding bolt h, which carries side lugs or a cross-piece h², that connects by springs i with the inner end of the carriage E, as shown in Figs. 4 and 5.

G G are clamp-plates for clamping the carriage E to the tube A. These clamp-plates are pivotally connected at j to the laterally-slotted cross-piece h², the pivot-pins j passing also into slanting or converging slots l of the plates e. The outer end of each clamp-plate has a 35 pin m, that enters into a slanting slot n provided for its reception in the plate e. The edges of the two clamps G G, that face each other, are respectively parallel with the inclination of the slots l n and are in contact with friction-rollers o, which are carried by the carriage E, being hung in the plates e. It will appear 40 from a comparison of Figs. 4 and 5 that whenever the bolt h is moved outward—that is, to the right in Fig. 4—so as to strain the springs i the clamps G G will be made to approach one another, whereas whenever the bolt h is 45 drawn inward by the springs i, as in Fig. 5, it will draw the clamps with it, and will thereby bring them into the outer parts of the 50 slots l n, so as to expand said clamps. It follows that whenever the springs i are not strained the clamps are expanded sufficient to securely hold the carriage fast in the tube, but that whenever the springs i are extended 55 the clamps are loosened, being drawn inward.

As far as I have now described the construction of the carriage E the foregoing description applies to the construction also of the inner carriage D, and I shall not, therefore, 60 give any further attention to the description of the inner carriage, except to state that the inner carriage is securely attached to the

stem or shank C by the pin or bolt a, as in Figs. 9 and 10; but the outer carriage E has one additional element which is not found in 70 the inner—to wit, a pulley or friction-roller p, secured in its outer end, for receiving around it a rope H, by which the instrument is actuated.

Having now fully described the construction of my mechanism, I will proceed to describe its operation. A wire, cable, or thread to be passed through the tube A is attached, as in Fig. 1, to the outer end of the stem or shank C—namely, to the pin d, which for this 75 purpose is formed on the said stem or shank; but of course any other means for permitting a convenient attachment of the wires may be provided on the said stem or shank. The rope H is now laid around the pulley p, and 80 one end of said rope is then tied to the pin d. The other end of the rope is free to be grasped by the operator and must be of a length at least equal to the length of the tube A. The instrument which I have described, and which 85 is now ready for operation, is now inserted into the tube A through one open end of said tube, it being of course understood that the clamps G G on the carriages are so proportioned that when expanded they will securely 90 hold their respective carriages in the tube. When now the attendant pulls on the free end of the rope H, the first effect is to draw the carriage E slightly outward until the clamps G take a tight hold on the inner face 95 of the tube A, the springs i of the carriage E being unstrained at this stage of the proceeding. A further pull on the rope will now 100 propel the stem C forward, and with it the inner carriage D, which, as soon as the inward motion commences, strains its springs i, and thereby releases its hold on the tube. Hence 105 as long as the operator pulls on the rope the carriage E remains stationary, and the stem or shank C, with the carriage D, is moved or 110 drawn inward into the tube. Thereupon—that is, as soon as the pin d has approached the pulley p as near as practicable—the operator lets go of the rope H, and immediately 115 upon so doing the clamps G of the inner carriage grip the inner side of the tube and hold fast, thereby enabling the springs F F to pull the outer carriage E inward, which said springs are enabled to do because the clamps G of the outer carriage relax their hold the 120 moment the inward pull begins. In other words, each of the carriages is arranged to automatically clamp itself in the tube when 125 there is no strain upon it or when there is a strain or pull upon it in an outward direction and to automatically let go of this grip as soon as a pull in an inward direction is applied, and thus it is that while the attendant pulls on the rope H the carriage E is stationary and the carriage D is advanced by the direct pull of the operator, and that when the attendant lets go of the 130 rope the carriage D remains stationary and the carriage E is advanced by the contrac-

tion of the springs F, and thus by a step-by-step motion the alternate pulling and relaxing of the rope H causes the entire machinery which I have thus described to pass along in the tube A until finally it emanates from the farther open end thereof or reaches any other desired position therein. From this farther end the entire machine can be conveniently withdrawn from the tube, because, as I have already stated, both sets of clamps relax their hold as soon as their respective carriages are moved in the direction which I have termed the "inward direction," which will be the discharge direction at the farther end of the tube.

The modification which is shown in Figs. 11 and 12 differs from the construction herefore described only in the location of the pulley p and spring F. In this modification the pulley p is hung in the inner carriage D, and the two carriages D E are not connected together by the spring F; but instead the spring F connects the outer carriage E with the outer part of the stem or shank C, the result being that when the rope H is pulled the inner carriage D remains stationary, the outer carriage E is pulled inward, and the spring F strained, and when, afterward, the rope H is relaxed the outer carriage E clamps itself tight, allowing the spring F to pull the shank C, and with it the inner carriage D, ahead, and so on.

Having now described my invention, what I claim as new, and desire to secure by Letters Patent, is—

1. In a wire-threading device, the combination of the shank C with a self-clamping carriage D, rigidly fastened thereto, and with another clamping-carriage E, which runs on said shank C, and with a contracting spring or 40 springs F for drawing the carriages toward each other, substantially as herein shown and described.

2. In a wire-threading device, the combination of the shank C, the carriages D E, the 45 contracting spring F between said carriages, the pulley p on the running carriage E, and the rope H, fastened to shank C by the pin d, all arranged substantially as specified.

3. The carriage E, composed of the plates e 50 and the vertical connecting-pieces g, in combination with the sliding bolt h, bolt-springs i, and clamps G G, the plates e being provided with slanting slots to permit of an outward and inward motion of the clamps, substantially as 55 herein shown and described.

4. In a wire-threading device, the combination of the shank C, the contracting springs F, and the carriages D E, each of said carriages being composed of plates e, a sliding 60 bolt h, the bolt-springs i, the clamps G G, and the vertical plate-connecting piece g, said plates e having diverging slots which permit the outward and inward motion of the clamps, substantially as specified.

FERDINAND A. WESSEL.
